INFANT'S CHAIR

Earl F. Hamilton and Ralph B. Lay, Columbus, Ind., assignors to Hamilton Cosco, Inc., Columbus, Ind., a corporation of Indiana

Original design application Feb. 12, 1962, Ser. No. 68,786.
Divided and this application Sept. 25, 1962, Ser. No.
71,855

Term of patent 14 years

(Cl. D15—1)

Fig. 1.

Fig. 2.

Fig. 3.

FIG. 1 is a perspective view of an infant's chair showing our new design;

FIG. 2 is a side elevation of the chair shown in FIG. 1, but showing said chair in its reclining position; and

FIG. 3 is a rear elevation of the chair shown in FIG. 1.

This application is a divisional application of our co-pending application Serial No. D. 68,786, filed February 12, 1962.

We claim:

The ornamental design for an infant's chair, as shown.
